BUCKET SEAT SHELL

Steve T. McQueen, 14732 Oxnard St.,
Los Angeles, Calif. 91401

Filed Jan. 12, 1970, Ser. No. 20,900

Term of patent 14 years

Int. Cl. D6—01

U.S. Cl. D15—8

Fig. 4

Fig. 5

FIG. 1 is a front perspective view of a bucket seat shell embodying my new design;

FIG. 2 is a side elevational view thereof;

FIG. 3 is a front elevational view thereof;

FIG. 4 is a top plan view thereof; and

FIG. 5 is a rear elevational view thereof.

I claim:

The ornamental design for a bucket seat shell, as shown.
